Primary Examiner — Paula Allen Greene(74) *Attorney, Agent, or Firm* — Justin Lampel(57) **CLAIM**

The ornamental design for a microphone set, as shown and described.

DESCRIPTION

FIG. 1 is a front, right and top perspective view of a microphone set, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising an edge of a net cover.

FIG. 10 is a partial enlarged view of an area labeled 10 in FIG. 1 comprising an edge of a microphone.

FIG. 11 is a partial enlarged view of an area labeled 11 in FIG. 1 comprising an adjusting knob.

FIG. 12 is a partial enlarged view of an area labeled 12 in FIG. 1 comprising an adjusting knob; and,

FIG. 13 is an exploded view thereof.

The broken lines shown in the drawings are included for the purpose of illustrating portions of the microphone set that form no part of the claimed design.

The dot dash dot broken lines encircling portions of the microphone set in FIG. 1 and illustrated in enlarged views of FIGS. 9 through 12 form no part of the claimed design.
